Attorney

UNITED STATES PATENT OFFICE.

CHARLES DAVID BONSALL, OF NEW KENSINGTON, PENNSYLVANIA, ASSIGNOR TO UNION METAL PRODUCTS COMPANY, OF CHICAGO, ILLINOIS, A CORPORATION OF DELAWARE.

END WALL FOR RAILWAY CARS.

Application filed October 12, 1926. Serial No. 141,200.

My invention relates to the construction of a railway car having an end wall made of one or more metallic plates or panels secured together and formed with integral reinforcing and stiffening means to resist the thrust of shifting loads. While efforts are made to block the lading in the car, the shocks caused by the heavy locomotives, the emergency air brake and the classification 5 hump tear the lading away from its moorings and throw it against the end of the car. The invention is readily adaptable to box, gondola and other types of railway cars.

One of the objects of the invention is to provide a wall element which has great strength to resist the torsional and weaving stresses which exist in a railway car when moving in service. These stresses are caused by the inertia of the roof and superstructure 15 when the train is suddenly stopped; rough or uneven track; the superelevation of the track on curves; the lateral inertia in rounding curves; eccentric thrust due to the lading being secured to one side of the car; the 20 cars being "cornered"; the use of push pole pockets, etc. Such stresses rack and distort the superstructure which decreases the life 25 of the car, and also causes the car to leak grain, sand, and other such material. Furthermore, such stresses cause leaky roofs 30 and leaky and inoperative side and end doors.

An object of the invention is to form the meeting edges of the metallic plates of an 35 end wall so as to provide an integral stiffener or beam.

In the drawings:

Fig. 1 shows an end of a railway box car with my device applied thereon.

Fig. 2 is a section on line 2—2 of Fig. 1.

Fig. 3 is a section on line 3—3 of Fig. 1.

Fig. 4 shows a modified form.

In the drawings the usual parts of the car are shown, such as end sill 1; end plate 2 45 and corner post 3.

In the preferred form the end wall comprises a central metallic plate 4 which is bent adjacent each vertical edge to form a web 5, which web is bent to form a flange 6. On each side of the central plate is a metallic plate 7 having a similar web 8 and flange 9 at their respective margins adjacent the central plate. Each of the flanges of the

central plate is secured to one of the side plates and the flanges of the side plates are 55 each secured to the central plate and spaces 10 are provided between the adjacent webs of the side and central plates, respectively.

This overlapping construction forms a very strong box girder which is capable of 60 acting as a post to sustain the roof loads of the car and also forms a very strong beam to resist the horizontal loads imposed upon the end wall and transmit them to the end sill and end plate, respectively, and 65 furthermore, acts as a stiffener to prevent the end wall from buckling due to the lateral stresses in the car. This box girder is also 70 weatherproof. This construction can be formed by simply bending the plates and does not necessitate any heating thereof.

In the form illustrated, the central plate is formed with a continuous web and flange around its perimeter so as to form an embossment and the web and flange of the side 75 plates are positioned within the embossment and are made shorter than the length of the side plates for this purpose.

Fig. 4 shows a modified form wherein the side plates 11 are each provided with an 80 embossment and the webs and flanges of the central plate 12 are terminated within the embossments of the side plate.

Various combinations of embossed and plain plates may be used and also any number of plates may be used and the box 85 girders may be of different depths in the same end wall if desired and all of these modifications would come within the scope of the invention, but for convenience, I have 90 shown and described an end wall comprising only three plates.

The width of the space 10 between adjacent webs of the adjacent plates may be varied if desired (as shown in Fig. 4) as 95 the strength of the box girder construction to resist horizontal loads from the inside of the car will vary according to the width of this space.

The wooden lining 13 is nailed to the 100 nailing strip 14 which are secured (preferably bolted) to the end wall adjacent the box girder.

I claim:

1. An end wall for a railway car comprising two metallic plates, each formed 105

with a body, a web, and a flange, the flange of each plate secured to the body of the other plate with a space between said webs.

2. An end wall for a railway car comprising two metallic plates, each formed with a body, a web, and a flange, the flange of each plate secured to the body of the other plate with a space between said webs substantially equal in width to the depth of

10 said webs.

3. An end wall for a railway car comprising a central plate having a web, and a flange on each outer margin, and a metallic plate on each side of said central plate having a web and a flange at their respective margins adjacent said central plate, each flange of said central plate secured to one of the side plates and the flanges of the side plates each secured to the central plate

20 and a space between adjacent webs.

4. An end wall for a railway car comprising a central plate having a continuous web, and a flange around its perimeter forming an embossment, and a metallic plate on each side of said central plate having a web and a flange at their respective margins adjacent said central plate, the flanges on the opposite sides of the central plate each secured to one of the side plates and the flanges on the side plates each secured to the central plate and a space between adjacent webs.

5. An end wall for a railway car comprising a plate having a continuous web and flange around its perimeter forming an embossment, and a metallic plate having a web and a flange at one side thereof positioned within said embossment, the flange of each plate secured to the body of the other plate with a space between the webs.

CHARLES DAVID BONSALL.
